US0D1060388S

(12) **United States Design Patent** (10) **Patent No.:** **US D1,060,388 S**
Kim et al. (45) **Date of Patent:** **** Feb. 4, 2025**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Yejin Kim**, Suwon-si (KR); **Jonwoo Shin**, Suwon-si (KR)

(73) Assignee: **Samsung Electronics Co., Ltd.**, Suwon-si (KR)

(**) Term: **15 Years**

(21) Appl. No.: **29/881,255**

(22) Filed: **Dec. 29, 2022**

(30) **Foreign Application Priority Data**

Jul. 14, 2022 (KR) 30-2022-0028444

(51) **LOC (15) Cl.** **14-04**

CLAIM

The ornamental design for a display screen or portion thereof with graphical user interface, as shown and described.

DESCRIPTION

FIG. 1 is a front view of a display screen or portion thereof with graphical user interface showing our new design according to a first embodiment; and,

FIG. 2 is a front view of a display screen or portion thereof with graphical user interface showing our new design according to a second embodiment.

The outermost perimeter broken line in each drawing figure depicts a display screen or portion thereof and forms no part of the claimed design.

The remaining broken lines in the figures depict portions of the graphical user interface that form no part of the claimed design.

1 Claim, 2 Drawing Sheets
